CLAIM

The ornamental design for a combined container with lid, as shown and described.

DESCRIPTION

FIG. 1 is a front, top perspective view of a combined container with lid showing my new design;
FIG. 2 is a front elevation view thereof;
FIG. 3 is a rear elevation view thereof;
FIG. 4 is an enlarged left side elevation view thereof;
FIG. 5 is an enlarged right side elevation view thereof;
FIG. 6 is a top plan view thereof;
FIG. 7 is a bottom plan view thereof; and,
FIG. 8 is a perspective view thereof, showing the article in use.

The broken lines shown in the figures depict portions of the combined container with lid that form no part of the claimed design.

1 Claim, 8 Drawing Sheets
